UNITED STATES PATENT OFFICE.

GEORGE W. WAREHAM, OF PITTSBURG, PENNSYLVANIA.

MATTRESS-FILLER.

SPECIFICATION forming part of Letters Patent No. 697,045, dated April 8, 1902.

Application filed March 28, 1901. Serial No. 53,191. (No model.)

To all whom it may concern:

Be it known that I, GEORGE W. WAREHAM, a citizen of the United States, residing at Pittsburg, in the State of Pennsylvania, have 5 invented certain new and useful Improvements in Frictionless Mattress-Fillers, of which the following is a specification.

This invention relates to mattress-filling machines.

10 Among the objects of the invention are to provide a machine to fill mattresses of various sizes, to place the filling material in the mattress without friction between the tick and filling material, and of such construction that 15 the filling can be done conveniently, quickly, and perfectly.

In the accompanying drawings, Figure 1 is a plan view, with portion broken away; Fig. 2, a side elevation of the same. Fig. 3 is a 20 detail perspective view.

The same characters refer to like parts in the views.

The numeral 1 designates the frame, provided with suitable legs 2. To the four corners of the frame 1 are arranged sprocket-wheels 3, over each two of which runs an endless chain 4, provided with transverse strips 5, on which rests the removing-sheets 6 and 6', which carry the filling material and form 30 a conveyer 36 for the latter. On the rear end of each sheet is permanently secured an end piece 7, the side piece 8 being independent of said sheets. The rear end pieces 7, with the sides 8 and a vertical reciprocating gate 32, 35 form a rectangular box, in which is placed and measured the filling material prior to the same being forced into the tick. The removing-sheet 6' slides transversely over the sheet 6, by which the width of the filling material is determined to suit the width of the tick. This adjustment is obtained through the medium of a sliding rail 9, the ends of which are attached to sprocket-chains 10. On a shaft 13 are keyed the sprocket-wheels 11, 40 which are connected to similar sprocket-wheels 12 by means of the chains 10. By rotating the crank 14, with which the shaft 13 is provided, the rail 9 can be moved in either direction. The rail 9 extends beyond the end 45 of the side 8 and is provided with an angle-iron *a*, an arm of which projects over the face of the end piece 7 of sheet 6', said arm hav-

ing a hole or perforation arranged to receive a pin *b* in said end piece. When the removing-sheets are in position to receive the filling material, the pin *b* projects through the hole or perforation in the angle-plate *a*, whereupon the end piece 7, together with the sheet 6', will move back and forth with the rail 9. When said removing-sheets are fed forward, 60 the pin *b* withdraws from said perforation, and upon return of said sheets re-enters the perforation, the angle-iron serving as a stop.

The front end of the machine is provided with two uprights 15, carrying the shaft 16, 65 and the latter is provided with radial arms 17, on each end of which rotates the roller 18, which latter is lowered by moving the lever 19 so as to place the roller in the position shown by dotted lines in Fig. 2. The roller 70 is rotated by means of the sprocket-wheels 20, running loosely on the shaft 16, and 21, attached to the roller-shaft 22, and chain 23, running over the sprocket-wheels, the wheel 20 being rotated by a similar wheel 25, attached 75 to wheel 20, chain 24, sprocket-wheel 26, gears 27 28, and hand-crank 29, the latter also operating the sprocket-wheels 3 and endless chains 4, carrying the transverse slats 5, on which the removing-sheets 6 and 6' rest. 80

To the front end of the machine are arranged the tick-supports 30 30', over which the tick is placed prior to filling, the latter being held to its place in relation to the supports 30 30' while being filled by the spring-clamps 31 31', the support 30' and spring 31' being attached to the sliding rail 9, by which they assume the same location as rail 9 to suit the width of the tick to be filled.

The vertical sliding gate 32 moves in guides 90 33 and is raised and lowered by means of the cables 34, attached to both ends of the gate and running over pulleys 35 and secured to the shaft 16, by which when the latter is rotated the gate 32 is raised or lowered.

Underneath the chains 4 are arranged a guideway 37 to support the chains 4 and prevent the latter from sagging when the filling material is placed on the conveyer 36.

In the operation of the machine the sliding 100 rail 9 is moved toward the center of the machine to a position to suit the width of the tick to be filled by rotating the crank 14, which moves the chains 10 10, and the rail 9

and support 30', being attached thereto, are shifted according to the direction of the motion imparted to the crank 14. The tick is then placed over the supports 30 30' in a 5 crimped condition, the spring-clamps 31 31' holding it in that condition temporarily. The filling material is then placed on the conveyer 36 and distributed properly thereon between the sides 8 8, ends 7 7, and gate 32, which is 10 then in its lowered position. The roller 18 is then lowered by the lever 19 being partially rotated, and the radial arms 17, attached to the shaft 16 and carrying the roller 18, lowers the latter to the position shown by the dotted 15 line, Fig. 2. This position of the roller 18 compresses the filling material to the proper thickness to suit the tick, which being on the supports 30 30' is in a position to receive the filling material. The rotation of the shaft 16 20 also lifts the gate 32 by the cords or cables 34, winding on shaft 16, and opens that end of the box to permit the ejection of the filling material. The crank 29 is then rotated, which through the sprocket-wheel and chain mechanism 25 rotates the roller 18. Simultaneously therewith the sprocket-wheels 3 are rotated and the slats 5 of the endless chains engage suitable projections on the bottom of the removing-sheets 6 6', forming the conveyer, 30 moving them forward in unison with the movement of the roller 18, thus compressing the filling material and feeding it with the removing-sheets 6 6' into the tick, which as it is filled is gradually forced off of the supports 30 30', and the movement continuing the tick is rapidly and evenly filled with the filling material. It will be noted that neither 35 the rail 9 nor the side pieces 8 enter the tick, the spring-clamps 31 31' permitting the tick 40 to be freed from the supports as it is filled until the operation is wholly accomplished. The roller 18 is then raised by actuating the lever 19, which also drops the gate 32, and the machine is then backed by turning the 45 crank 29, which withdraws the removing-sheets 6 6' from between the ticking and filling material, allowing the filled mattress to be removed ready for the upholsterer. The machine is then ready for filling another tick by 50 a repetition of the above operation.

By this machine mattress-ticks are quickly, conveniently, and perfectly filled in a superior manner and the compressing and feeding of the filling material simultaneously accomplished. Also the machine can be quickly and conveniently readjusted to fill any-sized tick by simply operating the crank 14 to increase or diminish the width of the conveyer 36 or rectangular receptacle formed by the 55 gate 32, sides 8 8, ends 7 7, and removing-sheets 6 6'.

The advantage of the radial adjustment of the roller 18 lies in the fact that said roller can be readily raised up out of the way of the 60 operator while the filling material is being placed on the removing-sheets. A further

advantage is also obtained by this construction in the ease with which the thickness of the filling material may be regulated, the use of adjusting-bolts, &c., being entirely dispensed with. 70

Having thus described the invention, what I claim, and desire to secure by Letters Patent, is—

1. A mattress-filling machine comprising a 75 supporting-frame, an adjustable roller mounted therein, a sliding gate, and means for simultaneously adjusting said roller and operating said gate, as set forth.

2. A mattress-filling machine comprising a 80 frame, a roller mounted therein, means for adjusting said roller angularly, a conveyer comprising two removing-sheets, means for varying the width of said conveyer, and means for simultaneously operating said conveyer 85 and rotating said roller, as set forth.

3. A mattress-filling machine comprising a supporting-frame, an adjustable roller mounted therein, means for adjusting the same, a conveyer, a sliding gate, and connections between 90 said roller and said gate, whereby they are moved simultaneously, as set forth.

4. A mattress-filling machine comprising a supporting-frame, an adjustable roller mounted therein, means for adjusting the same, a 95 conveyer, a sliding gate, connections between said roller and said gate, whereby they are moved simultaneously, and means for simultaneously operating said conveyer and rotating said roller, substantially as set forth. 100

5. A mattress-filling machine comprising a supporting-frame, an adjustable roller mounted therein, means for adjusting the same, a conveyer, a sliding gate, a lever pivoted in said frame and having connections with said 105 roller, and connections between said lever and said sliding gate, substantially as set forth.

6. A mattress-filling machine comprising a supporting-frame, a shaft mounted therein 110 and having radial arms, a roller mounted between said arms, a lever connected to said shaft, a conveyer, a sliding gate, and connections between said lever and said gate, substantially as set forth. 115

7. A mattress-filling machine comprising a supporting-frame, a shaft mounted therein and having radial arms, sprocket-wheels mounted loosely on said shaft, a roller mounted between said arms and carrying sprocket-wheels on each end, chains connecting the sprocket-wheels of said roller with those of 120 said shaft, means for rotating said latter sprocket-wheels, a lever connected to said shaft, a conveyer, a sliding gate, and connections between said lever and said gate, substantially as set forth. 125

8. A mattress-filling machine comprising a supporting-frame, a conveyer mounted therein, removing-sheets arranged to be fed thereby, sprocket-chains arranged to vary the relative positions of said removing-sheets, a slid- 130

ing gate mounted in said frame, means for operating the same and means for operating said conveyer, as set forth.

9. A mattress-filling machine comprising a supporting-frame, a conveyer mounted therein, removing-sheets arranged to be fed thereby, a rail connected to one of said removing-sheets, means for adjusting said rail, and means for operating said conveyer, substantially as set forth.

10. A mattress-filling machine comprising a supporting-frame, a conveyer mounted therein, removing-sheets arranged to be fed thereby, sprocket-wheels mounted in said frame, chains connecting said wheels, a rail connected to one of said removing-sheets and also to said chains, means for rotating said sprocket-wheels, and means for operating said conveyer, substantially as set forth.

11. A mattress-filling machine comprising a supporting-frame, a conveyer mounted therein, tick-supports one of which is adjustable with relation to the other, removing-sheets arranged to be fed by said conveyer, and means for simultaneously adjusting said tick-supports and said removing-sheets, as set forth.

12. A mattress-filling machine comprising a supporting-frame, a conveyer mounted therein, removing-sheets arranged to be fed thereby, a rail connected to one of said removing-

sheets, tick-supports, one of which is connected to said rail, and means for adjusting said rail, substantially as set forth.

13. A mattress-filling machine comprising a supporting-frame, a roller mounted therein, means for adjusting said roller radially, a sliding gate, connections between said roller and said gate whereby they are both operated simultaneously, a conveyer, means for operating the same, removing-sheets carried by said conveyer, and means for adjusting the width thereof, substantially as set forth.

14. A mattress-filling machine comprising a supporting-frame, a roller mounted therein, means for adjusting said roller radially, a sliding gate, connections between said roller and said gate whereby they are both operated simultaneously, a conveyer, means for operating the same, removing-sheets carried by said conveyer, a rail connected to one of said removing-sheets, tick-supports one of which is connected to said rail, and means for varying the position of said rail, substantially as set forth.

In testimony whereof I affix my signature in the presence of two witnesses.
